CLAIM

We claim the ornamental design for a combined pet feeder stand with dual pet feeder bowls, as shown and described.

DESCRIPTION

FIG. 1 is a perspective view of a combined pet feeder stand and dual pet feeder bowls showing our new design;

FIG. 2 is a front elevational view, the opposite side being a mirror image thereof;

FIG. 3 is a left side elevational view, the opposite side being a mirror image thereof;

FIG. 4 is a top plan view thereof;

FIG. 5 is a bottom plan view thereof;

FIG. 6 is a perspective view of the pet feeder stand shown alone, for clarity of illustration;

FIG. 7 is a front elevational view, the opposite side being a mirror image thereof;

FIG. 8 is a left side elevational view, the opposite side being a mirror image thereof;

FIG. 9 is a top plan view thereof; and,

FIG. 10 is a bottom plan view thereof.
